DESIGN FOR AN ELECTRICAL ORNAMENT

Anton Pfau, Portland, Oreg., assignor of one-half
to Thomas G. Rosson, Portland, Oreg.

Application October 24, 1936, Serial No. 65,486

Term of patent 7 years

To all whom it may concern:

Be it known that I, Anton Pfau, a citizen of the United States and a resident of Portland, in the county of Multnomah, State of Oregon, have invented a new, original, and ornamental Design for an Electrical Ornament, of which the following is a specification, reference being had to the accompanying drawing, forming a part thereof.

Figure 1 is a perspective view of an electrical ornament showing my new design.

Figure 2 is a front elevation of the ornament illustrated in Figure 1.

Figure 3 is a side elevation of the ornament, partially in section.

I claim:

The ornamental design for an electrical ornament as shown.

ANTON PFAU.
